UNITED STATES PATENT OFFICE.

MILAN W. HALL, OF NEW ROCHELLE, NEW YORK.

ANCHOR.

Application filed February 2, 1924. Serial No. 690,111.

This invention relates to anchors for ships' use, and my improvements are directed to that type of anchor having pivotal flukes. Usually, with this type of anchor the flukes 5 are crowned with an abutment structure which engages the surface the flukes are intended to penetrate; and thereby limits the degree to which the flukes can dig into the sand, mud or other bottom.

10 It is an object of my invention to entirely avoid this objection.

The flukes of my improved anchor are designed to present a broad, flat, plane surface, with as little abutment or resistance 15 effect as possible, the whole forward sides of the flukes being refined down to a relatively keen sharp cutting edge to enhance the penetrating qualities; the shank also is given a relatively broad flat section, having its 20 greatest thickness longitudinally along its center line, and tapering vertically each way to a cutting edge, the object being to reduce shank resistance to a minimum.

A further peculiarity of design is in the 25 construction of the pivot by which the flukes are attached to the shank, the shank being provided at each side with a trunnion or transverse bearing pin, constructed integral with the shank, and upon which the flukes 30 are pivotally supported, the object of this arrangement being to provide a suitable length of bearing to insure and preserve a central alignment of the shank with the flukes.

35 In order to fully realize the maximum holding value in this type of anchor, it is not alone sufficient to reduce the penetrating resistance to a minimum, but provisions must be made to eliminate an inherent defect characteristic of the double pivoted fluke 40 type of anchor, such defect being the liability of rolling over and breaking out under dragging conditions.

Some of the contributing causes for this 45 peculiarity of action are:

1st. Unequal earth resistance, causing one fluke to pull down faster than the other.

2nd. Non-alignment of shank with flukes, giving greater leverage to one fluke over 50 that of the other.

3rd. Shank resistance at the center line of anchor, producing a fulcrum effect upon which the anchor finds support for its rolling action.

55 To cure the anchor of these critical defects, the following provisions have been

made. Correct alignment of the shank is insured by the peculiar arrangement of pivotal bearing for shank and flukes.

The shank resistance at the center line of 60 anchor has been reduced to a minimum, eliminating the fulcrum effect upon which the anchor found support for its rolling action.

Neutralizing the unequal earth resistance 65 is achieved by using two widely separated trip members, placed near the outer sides of the flukes, and serving as stabilizers by introducing a balancing resistance when either fluke tends to advance downward ahead of 70 the other.

Anchors of the double pivoted fluke type have also proven deficient when it was found imperative to lay at short scope of the cable. All vessels lying at anchor with even a moderate wind blowing, have a perpetual yawing motion from side to side. This motion is transmitted through the cable to the anchor 75 and produces a similar swaying from side to side.

Owing to the fact that these anchors have two flukes hooked into the bottom, they cannot pivot readily upon the flukes as they 80 sway from side to side, and in consequence the swaying motion causes them to break out 85 and drag.

This deficiency is almost wholly eliminated or neutralized in my improved anchor, by the use of the thin wide shank, which buries down deep in the mud. When the 90 anchor hooks in, this broad shank provides a suitable resistance to absorb the swaying action of the vessel without disturbing the anchor, or causing it to break out and drag.

Other features and advantages of my invention will hereinafter appear.

In the drawing:

Figure 1 is a plan view of my improved anchor partly broken away, with the flukes 100 prone.

Fig. 2 is a partial side view thereof showing a fluke angled as in operation.

Fig. 3 is a section on the line 3—3 on Fig. 1, and

Fig. 4 is a section on the line 4—4 of 105 Fig. 2.

In said views let 1 indicate the shank, having at its free end a ring or eyelet 2 for engagement by a cable, and let 3, 4, respectively indicate trunnions which extend from opposite sides of the shank, at its other end. The flukes 5 and 6 are alike and each has in its 110

2
pivotal portion a tapered opening 7 to receive a trunnion, the bearing portions also being pierced with cylindrical bearing openings 8, whose axes are aligned and parallel 5 with the axes of the trunnions. A single bolt 9 extends through the bearings 8, lying cross-wise of the shank beyond the end thereof. The bearing portions of the flukes, which are spaced apart from each other, each 10 have a rearwardly extended lug 10, provided with aligned bolt holes to receive a bolt 11 that passes through a spacer 12, which carries a terminal trip line ring 13.

15 The spacer 12 is an angular member having the forward surfaces 14, which co-act with the end 15 of shank 1, and serve as stops, to limit the degree of angular movement of the flukes, the spacer being rigidly connected to the flukes by reason of bolt 9 20 passing therethrough.

25 Lateral equalizing means for the anchor, to prevent rolling action thereof and to cause its flukes to both enter the sand or mud bottom in operation, are here shown as a pair of angle members each having a web 16 and flange 17. The angle members are mounted by their webs upon the bolt 9, respectively near the ends thereof, to be thus widely spaced apart, their webs butting against the 30 opposite ends of the bearing portions of the flukes about the bearing openings 8, being secured by the bolt head 18 and nut 19. The flanges 17 lie transversely of the flukes, and are of sufficient length to serve 35 their purpose, which, as stated, is that of stabilizing the flukes, by preventing the anchor from turning unduly about its longitudinal axis, to cause greater engagement by one fluke than by the other.

40 The fluke bearing portions are recessed at 20 to accommodate the angle members, also the bolt head and nut, and the webs 16 have each a saddle-like recess 21, to fit over the bearing portions 22, whereby the

angle members become rigidly engaged with 45 the flukes.

It will be noted that the shank 1 is relatively broad in a plane perpendicular to the axis of its trunnions, is transversely narrow (see Fig. 4); while the flukes (see 50 Fig. 3) are relatively narrow in a plane perpendicular to the same axis, and transversely broad. The shank tapers toward its opposite edges 23, and the flukes taper toward their opposite edges 24. By these means 55 strength of the shank and flukes is provided, and they are each enabled to readily cut into the sand or mud bottom, from either side.

It will also be noted that the flukes are headless, the lines of their bearing portions 60 merging into the blade lines with a tapering effect, without providing any transverse abutment such as would tend to retard the entry of the flukes into the sand or mud bottom.

65 Variations within the spirit and scope of my invention are equally comprehended by the foregoing disclosure.

I claim:

1. The combination, in an anchor, of a 70 shank that is relatively broad in height and narrow in width throughout its length, said shank being tapered to cutting edges at both sides of its height, and flukes pivoted to said shank at opposite sides thereof.

75 2. The combination, in an anchor, of a shank longitudinally disposed in regard to its length and vertically disposed in regard to its width and being formed with upper and lower cutting edges, and flukes pivoted to the shank having their blades disposed transversely to a vertical plane passing through the shank, said fluke blades having cutting edges extending over their whole periphery.

80 Executed this 1st day of February, 1924.

85 MILAN W. HALL.
